THERAPEUTIC DEVICE

Leonard Fisher and Ralph Fisher,
San Francisco, Calif.

Application November 1, 1943, Serial No. 508,489

9 Claims. (Cl. 219—34)

This invention relates to therapeutic devices, particularly one in which heat and light are applied.

In Patent 2,097,455 of November 2, 1937, one of us disclosed a device wherein light, heat and vibration were employed therapeutically to advantage. We have now found that heat and light produced in accordance with this invention can be advantageously employed alone therapeutically in the treatment of extended exposed areas of the body.

It is well known that the generation of light is attended with heat. Consequently, if one attempts to apply light to any extended surface of the body, some amount of risk of burning the skin may be involved. In accordance with this invention we have devised a successful apparatus permitting intense light, particularly infra-red rays, to be applied to the body while little sensation of heat, except to a pleasant degree, is experienced. Over an extended period of time, devices utilizing the present invention for light and heat generation and application have been successfully employed therapeutically with complete safety.

In applying infra-red rays to the human body for treatment, particularly over extended areas, it was found that even though relatively cold sources for generating the infra-red rays were employed, a sensation of burning would be felt on the skin. This difficulty we have been able to overcome successfully by employing a reflecting device having a diameter and a radius of curvature so related to one another that aberration occurred. Thus, instead of the reflector focusing the infra-red rays at one or more points on the patient, convergence of the rays was avoided. The optical principles of aberration are well understood and need not be further expounded here. Aberration, we have found, is assisted if the reflector, instead of being a true reflector, is a diffusing reflector. To this end we have successfully employed devices having a reflecting surface such that the energy waves are broken up and scattered by the roughness or irregularity of their reflecting surface.

In the device disclosed in the aforementioned patent skin surface vibration was secured by vibration of an element in contact with the skin. We have now found that by vibrating the skin with sound waves, either in the phonic or the ultraphonic range, at the same time that the vibrated area is heated, burning is obviated and a deeper penetration of heat into the tissues is secured. The sound wave vibration apparently vibrates the skin and increases blood circulation.

This is effective to carry away heat reaching the skin and tissues into the adjacent area and to deeper tissues. Instead, the light and heat generation source, vibrating constantly, provides a generalized heat and light source, one effective over the entire area of the reflector without localization. In this way it is possible for a point source to be effective in generating heat or light which is reflected from a single point on the reflector constantly and is yet distributed over an area instead of being focused on one point. This in addition reduces any likelihood of burns or uncomfortable sensation of heat or light rays. In addition, the vibrating heat and light source tends to produce therapeutic energy effective in producing a relatively deep body penetration. Thus, instead of one continuous ray emanating from one focus, an energy flux is, in effect, generated which penetrates into the body tissue, causing more blood to circulate through the treatment area.

We have also discovered that advantageously subjection of the human body to heat and light rays may be varied; that is, the application can advantageously be an intermittent one with the application repeated at timed intervals for a definite period of time. This involves employment of a timing device; the inclusion of such a timing device also has the advantage that subjection of the patient to a treatment is not left to the whim of an operator, the timing device being set for a definite period of operation, preferably a cyclic one. In this way possible harm to the patient as from burning or excessive treatment is avoided.

The invention includes other objects and features of advantage, some of which, together with the foregoing, will appear hereinafter wherein the present preferred device embodying the invention is disclosed.

In the drawings accompanying and forming a part hereof,

Figure 1 is a side elevation illustrating a machine embodying the present invention.

Figure 2 is a wiring diagram.

Figure 3 is a side elevation partly in section through the reflector light source unit and certain associated supporting mechanism.

Figure 4 is a section along the line 4—4 of Figure 3 illustrating the construction of the vibrating unit.

Figure 5 is a section taken through adjusting means for the device while Figure 6 is a view taken along line 6—6 of Figure 5.

As appears in the drawings I provide a suitable base structure 1 movably supported by casters 8

upon a suitable supporting surface such as floor 8. A flexible cable 11 extends from the base to a suitable source of electrical energy. Mounted upon the base is a pedestal 12 extending upwardly to carry control panel 14 and provide a suitable support standard 16. The pedestal and support standard are preferably hollow to permit installation of suitable presently described wiring and electrical instruments and control devices employed in conjunction with therapeutic device 17. An extending hollow arm or boom 18 is adjustably mounted on the standard and extends therefrom to carry the presently described therapeutic device of this invention, the device being generally indicated at 17.

Means are provided for raising and lowering the arm or boom 18. Mounted upon the standard 16 is a suitable casting 19 slotted to receive an ear 21 formed as part of a casting 22. The ear is positioned on a shaft 26 which will now be further described. The shaft 26 has a head 27 thereon. Abutting the head and carried by a non-circular portion 28 is a worm wheel 29. The shaft is supported for rotation in casting 19 by circular portions 31 and 32. These are spaced apart by another non-circular portion 33 fitting in a cooperatively formed receptacle in ear 21. A stud 34 carrying a washer 36 is screwed into the shaft to retain it in place. The successive elements on the shaft, that is, non-circular portion 28, bearing 31, non-circular portion 33 and bearing 32 are each successively of smaller diameter. With the worm wheel in place, the shaft can be inserted in position and the stud and washer secured to retain the shaft in position. Thereafter closures 37 are placed in the casting 19 to enclose the worm wheel and the shaft. The worm wheel is engaged with a worm 41 carried upon a shaft 42 suitably mounted for rotation in casting 19. Shaft 42 also carries a worm wheel 43 engaged with a worm 44 on a shaft 46. In this manner a double reduction is effected and the position of the boom 18 can be adjusted nicely, shaft 46 extending from the casing and carrying hand wheel 48.

To support the boom and enable its position to be adjusted to a nicety, a bracket 51 is secured to the casting 19 by a stud 52 at one end thereof; at the other end of the bracket an ear 53 extended into a bifurcated end 54 on tube 56. A 50 plunger 57 is hinged as at 58 on the boom 18, the plunger extending into tube 56. A spring 59 is positioned in the tube to abut the plunger; the boom is thus supported flexibly by the bracket 51 and by the extensible arm provided by the plunger, spring and tube 56.

The angular position of the therapeutic device 17 on the end of the boom is readily adjusted and to this end we mount a casting 61 on the end of the boom. This casting is bifurcated as at 62 to receive the apertured ear 63 from the supporting head 64 of the therapeutic device. The position of the ear is adjusted by means of the bolt 66 and hand wheel 67, rotation of the hand wheel being effective to draw the bifurcated ends 62 of the casting 61 together to clamp the ear 63 in a selected position.

As appears in Figures 3 through 6, standard 16, casting 19, boom 18, casting 61 and ear 63 are apertured or channeled, as are the other devices in the path, to permit suitable cables for the distribution of electrical energy to the therapeutic device to be threaded unobtrusively through the apparatus.

The therapeutic device 17, as previously men-

tioned, includes a head casing structure 64. In this is mounted a magnetic core 71 having a suitable coil 72 wound thereon. A passage for a movable rod or plunger 73 is provided through the core. The plunger is movably supported from the core by a flexible and resilient S-shaped member 74 secured to the core as by rivets 76. The S-shaped member carries a magnetic member 75. These cooperate with the coil to provide an electromagnetic vibrator capable of vibrating rod or plunger 73 about 7,200 times per minute.

The plunger extends through the core to support and vibrate a heating element generally indicated at 77, the element including a ceramic base 78 on which is carried a metallic heating element 79, the ceramic base being engaged and positioned by a nut 80 on the rod 73. The upper end of the casing is closed by a suitable closure member 81. To the lower end of the casing is 20 attached a stationary reflector 82 and an outer stationary casing 83, the reflector being spaced from the outer casing to permit air circulation between the two so that one cannot touch the reflector and be burned if the reflector for any 25 reason should become heated. The heating element passes through an aperture in closure member 84 at the end of the reflector.

Across the face of the outer stationary shell 83 is provided a suitable grille 86. This is ordinarily made of a screen of relatively large mesh, a half inch or so. The screen is provided for protective reasons to ensure that one cannot touch the heating element and to retain any portions if the element should break and portions fall therefrom.

As I have previously mentioned, the form and nature of the reflector are highly important. The reflector diameter and curvature should be such that aberration occurs, that is, heat and light 40 waves generated by the heating element should not become focused at any point or even at any plurality of points but instead should generally be diffused more or less evenly across the entire area beneath the reflector. In this way one can 45 expose the human body safely without fear of burning the body either due to heat or infrared ray application.

Another highly important factor is the diffusing nature of the reflector. The reflector can accordingly be made of any material which will diffuse the reflected light and heat waves. Preferably we have employed spun, unpolished aluminum to provide a simple and inexpensive reflector structure.

Referring particularly to Figure 2 a suitable source of electrical energy is indicated by power lines 101 and 102. A suitable timing device indicated generally at 103 is provided, this device ordinarily controlling a relay 104 to handle the heavy current supplied by lines 101 and 102. The timing device is such that it controls the periods of energization as well as the periods of de-energization of the heating element segments 108, 109 and 110 as well as the vibrator so that one setting of the timing device causes the elements to be operated in a cyclic manner as will presently appear further herein. One side of vibrator coil 72 is connected to line 101 while the other side is connected by line 106 to switch 107 to relay 104 controlled by the timer. The vibrator can operate at various rates of vibration. We prefer a high rate, about 120 per second, but this can be less (25 per second) or more (240 per second).

In general, the rate of vibration to be employed should not be one which is objectionable to the patient and one can use any rate in the phonic or ultraphonic range. Of course, vibration at extremely high rates gives rise to special construction problems but these can be readily solved by those skilled in the art for they are purely mechanical problems entirely incidental to practice of the invention.

The heating element includes three segments 108, 109 and 110. These preferably are capable of supplying different degrees of heat. Each element is respectively connected by a line 111, 112 and 113 to line 101 while the other side of each element is respectively connected by a line 114, 115 and 116 to switches 117, 118 and 119 to line 106. A tell-tale lamp 120, 121 and 122 is connected in parallel with elements 108, 109 and 110. The lamps, switches and the timer are conveniently mounted on the panel 14.

Under the control of timer 103, the operator can selectively energize element 108, 109 or 110 by closing switches 117, 118 or 119 selectively. At the same time, the elements can be vibrated or permitted to heat without vibration depending upon whether or not switch 107 is closed. In one successful device the elements 108, 109 and 110 respectively had a power consumption of 200, 300 and 500 watts. These could be operated independently or together in any desired combination to provide heat from 200, 300, 500, 700, 800 or 1,000 watts of power; the element can be made to provide any desired heat output and with any number of sections.

Timer 103 is effective to permit energy supply to the selected heat unit, with or without the vibrator, for a selected time period, say 90 seconds. The timer then cuts off the power for say 30 seconds, whereupon it turns it on for another 90 seconds. The time intervals are by way of example and other intervals can be used in the cyclic operation.

From the foregoing we believe it will be clear that we have provided a new and novel therapeutic device which we intend to claim broadly herein within the scope of the appended claims.

This is a continuation in part of our application Serial Number 418,040, filed November 6, 1941.

We claim:

1. In a device of the character described, an aluminum reflector having a diffuse reflecting surface of a diameter and a curvature sufficient to produce substantial aberration, an electrical heating element extended substantially along the longitudinal axis of said reflector and spaced therefrom, means for energizing said elements independently of one another, and means for vibrating only said element at about 7,200 vibrations per minute.

2. In a device of the character described, an aluminum reflector having a diffuse reflecting surface of a diameter and a curvature sufficient to produce substantial aberration, an electrical

heating element extended substantially along the longitudinal axis of said reflector and spaced therefrom, and means for vibrating only said element at about 7,200 vibrations per minute.

3. In a device of the character described, an aluminum reflector having a diffuse reflecting surface of a diameter and a curvature sufficient to produce substantial aberration, an electrical heating element including a base and having a plurality of independent heating segments thereon, said element being positioned substantially along the longitudinal axis of said reflector and spaced therefrom, and means for rapidly vibrating only said element at a rate at least in the phonic range.

4. In a device of the character described, a reflector having a diameter and a curvature sufficient to produce substantial aberration, an electrical heating element including a base and having a plurality of independent heating segments thereon, said element being positioned substantially along the longitudinal axis of said reflector and spaced therefrom, and means for rapidly vibrating only said element at a rate at least in the phonic range.

5. In a device of the character described, an aluminum reflector having a diffuse reflecting surface of a diameter and a curvature sufficient to produce substantial aberration, an electrical heating element including a base and having a plurality of independent heating segments thereon, said element being positioned substantially along the longitudinal axis of said reflector and spaced therefrom, and means for rapidly vibrating only said element at a rate at least in the phonic range.

6. In a device of the character described, an aluminum reflector having a diffuse reflecting surface of a diameter and a curvature sufficient to produce substantial aberration, an electrical heating element extended substantially along the longitudinal axis of said reflector and spaced therefrom, and means for rapidly vibrating only said element at a rate at least in the phonic range.

7. In a device of the character described, a reflector having a diffuse reflecting surface, said reflector having a diameter and a curvature sufficient to produce substantial aberration, a heat source positioned cooperatively to said reflector for reflection of heat and light from said reflector, and means for rapidly vibrating only said source relative to said reflector at a rate at least in the phonic range.

8. In a device of the character described, a reflector, a heat source cooperatively positioned with respect to said reflector to supply light and heat waves thereto for reflection, and means for rapidly vibrating only said heat source at a rate at least in the phonic range.

9. In a device of the character described, a reflector, a heat source cooperatively positioned with respect to said reflector to supply light and heat waves thereto for reflection, and means for vibrating only said heat source at a rate in the ultraphonic range.

LEONARD FISHER.
RALPH FISHER.
